CLOTHESLINE

Alma E. Whelan, Altadena, Calif.

Application April 25, 1945, Serial No. 590,174

2 Claims. (Cl. 211—119.13)

1

This invention relates to a clothesline, and more particularly to such a clothesline adapted to be constructed of metallic sections or the like.

A primary object of this invention is the provision of an improved clothesline having means associated therewith adapted to perform the function of conventional clothes pins, such means being permanently associated with the line.

An additional important object of the invention is the provision of such a line provided with means whereby a plurality of independent sections may be readily connected together and/or disconnected as desired in order to form a line of any desired length.

A still further object of the invention is the provision of such a line wherein the clips associated therewith for holding the clothes to the line, are provided with improved resilient means whereby the same may be readily separated to release the clothes or insert the clothes therebetween, their normal resiliency serving to hold the clothes securely to the line.

Other objects reside in the provision of such a clothesline that will be sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and disclosed in the accompanying drawings wherein there is shown a preferred embodiment of this inventive concept.

In the drawings:

Figure 1 is a side elevational view of a fragment of clothesline constructed in accordance with this inventive concept, showing a plurality of interconnected sections, the extremity of one of which is affixed to a suitable support.

Figure 2 is an enlarged top plan view of portions of the structure shown in Figure 1, certain portions thereof being broken away to disclose underlying structure.

Figure 3 is an enlarged sectional view taken substantially along the line 3—3 of Figure 2.

Figure 4 is a sectional view taken substantially along the line 4—4 of Figure 3, and

Figure 5 is a fragmentary top plan view showing a constructional detail.

Similar reference characters refer to similar parts throughout the several views of the drawings.

Having reference now to the drawings, the clothesline of the instant invention is comprised of a plurality of sections, which may be double,

2

as generally indicated at 11, or single as generally indicated at 12, secured together in a manner to be more fully described hereinafter.

Each of the links 12 is comprised of a tubular member 14, provided in its upper face with two spaced slots or apertures 15, and at its base with a longitudinally extending slot 16. Adapted to extend upwardly through the slots 15 are a pair of projecting lugs 17 corrugated for reinforcement purposes as at 18, and provided with finger-grip portions 19, the lower extremities of which are transversely corrugated as at 20, and terminate in clothes gripping extremities 21, which the normal resiliency of the member 14 serves to hold in closed juxtaposition. Thus, it will be seen that when the finger-grip portions 19 are grasped, the slot is expanded by the members 21 to separate the members 21 and to provide means whereby clothes or the like may be inserted between them. Upon release of the finger-grip portions 19, the resiliency of the member 14 causes the clamping portions 21 to firmly grasp the clothes. The upper surfaces of each of the members 14 are provided with keyhole slots 22 adjacent one end 14' thereof, adapted to engage the shanks of studs 23, affixed to the opposite ends 14'' of adjacent sections 14, two studs being provided at each extremity 14'' of a section 14 and two corresponding keyhole apertures 22 being provided at the other extremity 14', the ends 14' are enlarged and adapted to overlie a substantial length of ends 14'' to provide a relatively rigid connection.

The double members 11 are identical in construction and operation to the single members just described, with the exception of the fact that tubular member 14³ is slightly greater than twice as long, and adapted to contain a pair of the clamping members instead of a single member.

An S-hook 28, the extremity of which is secured as by a link 29 to an I-bolt 30 secured in any suitable supporting surface 31, is adapted to engage in a slot 22 to support the extremities of the line.

From the foregoing it will now be seen that there is herein provided an improved clothesline accomplishing all of the objects of this invention and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a device of the character described in combination, a plurality of slotted resilient, tubular sections, said sections having cut-away portions at opposite ends thereof, keyhole apertures in the upper portions of one end thereof and studs at the other extremity the studs of one section being adapted to engage the slots of a second section, and clamping means secured in said tubular sections.
2. In a device of the character described in combination, a plurality of slotted resilient, tubu-

lar sections, said sections having cut-away portions at opposite ends thereof, keyhole apertures in the upper portions of one end thereof and studs at the other extremity, the studs of one section being adapted to engage the slots of a second section and clamping means secured in said tubular sections, said clamping means including angularly disposed members having their extremities extending through said slots and secured in abutting relation by the resiliency of said sections.

ALMA E. WHELAN.
